UNITED STATES PATENT OFFICE

HAZEL M. JACKSON, OF TUCSON, ARIZONA

GARMENT

Application filed May 9, 1931. Serial No. 536,240.

This invention appertains to new and useful improvements in garments, and more particularly to a lady's garment, particularly useful in the household.

The principal object of this invention is to provide a garment which can be worn in various ways to always present a clean surface, and particularly the front surface which generally becomes soiled easiest.

During the course of the following specification and claims, numerous important objects and advantages of the invention will become apparent to the reader.

In the drawings:—

15 Figure 1 represents a front elevational view of the garment worn in one way.

Fig. 2 represents a front elevational view of the garment worn in another way.

Fig. 3 represents a rear elevational view 20 of the garment as illustrated in Figs. 1 or 2.

Fig. 4 represents an outside elevational view of the garment in open position.

Fig. 5 represents an enlarged fragmentary detailed sectional view taken substantially on the line 5—5 of Fig. 4.

Fig. 6 represents an enlarged fragmentary detailed sectional view taken substantially on the line 6—6 of Fig. 4.

Fig. 7 represents an enlarged fragmentary 10 detailed sectional view, taken substantially on the line 7—7 of Fig. 4.

Fig. 8 represents a fragmentary detailed sectional view taken substantially on the line 8—8 of Fig. 4.

5 Referring to the drawings, wherein like numerals designate like parts, it can be seen that the garment includes the central section 5 and the two front sections 6—7. The sections 5, 6 and 7 are joined together by flat faced seams 8 and secured to the inner and outer sides of each of these seams 8 at the lower portion thereof, are the buttons 9 for cooperation with the button holes 10 in the outer edge portions of the front sections 6 and 7.

Each of the front sections is provided with a tie strip 11 which is adapted for disposition thru the slit 12 in the other front flap or section. In other words, the tie strip 11 of the front section 6 will pass through the

slit 12 of section 7, while the tie of the section 7 will pass thru the slit 12 of the section 6. The sections 6 and 7 are provided with pockets 13 and arm openings 14 are provided between the front sections and the intermediate section 5.

It can now be observed, that the section 5 is essentially the back of the garment, while the sections 6 and 7 are interchangeable fronts for the garment. In other words, the section 7 can be disposed over the section 6 as shown in Fig. 2, or, as when the section 7 becomes soiled, the section 6 can be disposed over the section 7 and in each instance, a pocket 13 will be exposed for use.

The buttons 9 are both on the inner side and outer side of the garment, so that they can be engaged through the button holes 10 to secure the front sections to the seams 8 in the manner clearly shown in Figs. 1 and 2. Furthermore, the tie strips 11 are disposed rearwardly and can be tied in a bow as shown.

Obviously, the inside or the outside of the garment can be used, both being identical, and in this connection, the inner side or the outer side of each front section 6 and 7 can be employed. In this respect, the garment may be regarded as a four-way piece of apparel, and manifestly, may be worn for a considerable period of time without washing, especially when the soiled parts of the garment sections are not particularly disagreeable.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

1. A reversible garment including a back section, and opposed front sections secured to the back section and adapted to be lapped either over the other when in either an obverse or reverse position; said garment having a slit at each side at about the waist line and at the regions where the front sections adjoin the back section, and each front section being provided with a tie strand joined

thereto in substantial alinement with said slits, the tie strand of the inner front section passing through the slit adjacent the outer front section to the exterior of the garment when in either an obverse or reverse position; a vertical row of buttons on the inner and outer sides of the garment adjacent the junction of each front section with the back section, and with the uppermost 10 button of each row spaced downwardly a material distance from the waist line each front section being also provided with a vertical row of button holes adjacent its free edge and in substantial alinement with the 15 buttons; either inner lapped front section being adapted to be buttoned to the inner buttons adjacent the opposite front section, and the latter front section being adapted to be buttoned to the outer buttons adjacent 20 the inner lapped front section, when the garment is in either an obverse or reverse position.

2. A reversible garment open in front from top to bottom, and presenting a pair of opposed front sections, each of which sections is 25 provided with a slit spaced inwardly from the junction of the front section with the body of the garment at about the waist line, and being also provided adjacent a free edge with 30 a tie strand joined thereto at about the waist line; each front section being also provided with a vertical row of button holes adjacent the bottom of the garment in proximity to said edge; a vertical row of buttons on the 35 inner and outer sides of the garment adjacent the bottom of the garment and at the junction of each front section with the body of the garment; said front sections being adapted to be lapped, when the garment is in 40 either obverse or reverse position, either over the other and with the lapped front section buttoned to the inner row of buttons adjacent the overlapping front section, the overlapping front section buttoned to the outer row 45 of buttons adjacent the lapped front section, and the tie strand of the lapped front section passing through the slit of the overlapping front section to the exterior of the garment.

50 In testimony whereof I affix my signature.
HAZEL M. JACKSON.
